Philip D. McLean

ATTORNEY

UNITED STATES PATENT OFFICE.

LOUIS E. BALTZLEY, OF GLEN RIDGE, NEW JERSEY.

PAPER CLIP.

Application filed August 9, 1921. Serial No. 490,862.

The general objects of my present invention are to provide a clip or temporary binder for holding loose papers and the like which will be simple and inexpensive in its 5 construction and which will combine the advantages of secure holding force and ease of operation.

Further special objects are to provide a clip of this character which can be inexpensively produced by simple operations 10 from a one piece sheet metal blank.

In the drawing accompanying and forming part of this specification I have disclosed different embodiments of the invention, and a novel method of manufacturing 15 the same, but as these disclosures are primarily illustrative in character, it will be understood that the structure and process of manufacture may be varied without departure from the true spirit and scope of the invention as hereinafter defined and claimed. In this connection also I would have it understood that the terms which I have employed herein are used in a descriptive 20 rather than in a limiting sense, except for such limitations as may be required by the prior art.

Figure 1 in the drawing referred to is an edge view of the clip in its open, paper-receiving condition, with the closed position indicated in dotted lines.

Figure 2 is a plan view and

Figure 3 is a rear view of the clip as in its normal closed position.

Figures 4 to 8 are diagrammatic views 35 illustrating successive steps in the manufacture of the clip.

Figures 9 and 10 are edge and plan views 40 respectively of a slightly modified form of the device.

The reference characters 15, 16 designate the companion gripping jaws of the clip which are connected together at their opposite ends by integral springs hinges and are 45 operated by integral handle levers 17, 18, projecting rearwardly at points intermediate the spring hinges at the ends.

The spring hinges at the opposite ends of the jaws are separated, as indicated at 19, 20, 50 in Figure 3, and therefore more or less independent in their operation.

As best shown in the edge views, these 55 hinges each consist of a relatively flat intermediate connecting strap 21 provided at its opposite ends with rearwardly directed loops or reversely curved portions 22 connected

with the jaws by forwardly turned reversely curved portions 23.

These reversely curved portions operate as double spring connections between the 60 jaws and the connecting or spacing straps 21, providing sufficient flexibility to enable the use of relatively heavy gage sheet metal, which is desirable because of its greater 65 strength and durability.

The connecting straps 21 of the spring hinges when relatively flat and straight, as shown in Figure 1, may be utilized as edge gages for the papers inserted in the clip. As 70 shown in Figure 9, however, the intermediate connecting portion 21 of the spring hinge need not be straight, but may be curved, in continuation of the reverse curves at the opposite ends thereof.

An especially important feature of the invention is that the separation of the end hinges provides the necessary material for the jaw operating handles between the same. This will be best understood by reference to 75 Figures 4 to 8 wherein I have illustrated one 80 practical method of manufacturing the device.

In the first of these views, there is shown the sheet metal blank 24 from which the clip is made, said blank being of oblong construction providing the material for the clamp jaws at the opposite ends thereof and the material for the handle levers and spring hinges between these end portions. The first 85 operation on the blank is to make the substantially H-shaped cut, indicated at 25. The removal of this H-shaped section of metal from the intermediate portion of the blank defines the jaw handles at the central plane 90 and the spring hinge portions at the opposite longitudinal edges of the blank. The handle levers are thus initially formed as straight continuations of the clamping jaws and they retain this initial relation to the jaws throughout the remainder of the formation and use of the article. 95

To stiffen the handles and particularly at their juncture with the jaws, I preferably provide them with stiffening ribs 26 extending from the outer free ends of the handles, 105 inward well into the body of the jaws. In the first form of the invention I have shown two such stiffening ribs to each handle extending convergently along the edges of the handles, which are shown as tapered toward their outer and free ends and have further shown these stiffening ribs as connected at 110

the free ends of the handles by short transverse corrugations or ribs 27 providing somewhat rounded gripping surfaces for engagement by the fingers of the operator.

5 The second step in the process disclosed consists in forming these stiffening ribs in the jaw and handle portions of the blank, as indicated in Figure 5. The next step disclosed consists in bending the jaw ends of 10 the blank downward along the lines 28 (Figure 5) to carry the opposed jaws and handles into the substantially parallel relation shown in Figure 6. In the next operation, the intermediate portions of the end straps 15 connecting the jaws are struck downward, as shown in Figure 7, to start the formation of the double reverse curves for the spring hinges, after which it is only necessary to force the opposite sides together so as in 20 effect to fully break in the reverse curves of the hinges, care being taken during this latter operation to give a "set" to the hinges which will force the jaws normally together 25 into the convergent relation shown in Figure 8.

This method of construction is quite simple and the steps follow each other in logical sequence and an especially important advantage is that there is never any break 30 or weakening of material between the jaws and their operating handles, these parts being maintained in their initial straight and continuous relation.

The same method of procedure may be 35 employed in the manufacture of the second form of clip. In addition to the variation in the shape of the spring hinges it will be noted that in this second form of 40 clip there is only a single reinforcing rib extending from each handle into the body of its jaw. This means that a somewhat simpler form of "ribbing" die can be used in the manufacture of this clip.

The inner portions 21 of the spring hinges 45 constitute in effect the fulcrums for the hinging movement of the jaws and by displacing these fulcrums inwardly or toward the jaw tips, the leverage of the handles is increased so that the clips can be easily 50 opened despite their powerful gripping effect. This inward displacement of the fulcrum portions also is of advantage in that

it leaves the space between the opposed handles at the rear clear and unobstructed.

The inward displacement of the material 55 at this point furthermore, it will be noted, provides an abundance of material from which to form lever handles sufficiently long for easy operation of the clip.

What I claim is:

1. A clip of the character described, comprising cooperating clamping jaws connected at their opposite ends by longitudinally separated integral spring hinges and having integral lever handles projecting rearwardly therefrom at points intermediate the end 60 hinges, said handles standing in the same, planes with and forming straight continuations of the jaws and the material of the 65 hinges being bent to shorten the same and thereby increase the leverage of the handles.

2. A one piece sheet metal clip comprising a plate of spring metal bent to provide opposed clamping jaws connected by spring 70 hinges at the opposite ends of the jaws, the material of the plate between said end hinges being extended rearwardly of the jaws and forming operating handles therefor and the material of the hinges being displaced from the rear of the clip inwardly between the 75 jaws whereby to shorten the same and increase the leverage of the jaws.

3. A one piece sheet metal clip comprising a single plate of spring metal having opposed jaw portions connected at their opposite edges by integral hinge strips and the metal between such hinge strips consisting of integral handles projecting rearwardly from the jaws a considerable distance past the spring hinge strips and said 80 spring hinge strips being each buckled in the intermediate portion of the same to shorten said spring hinge strips to bring the 85 jaws closer together and provide hinge fulcrums at the juncture of said strips with the 90 jaws, the intermediate buckled portions of the separate hinge strips standing crosswise of the space between the jaws to act as a back stop for papers inserted between 95 the jaws.

In witness whereof, I have hereunto set my hand this 30 day of July, 1921.

LOUIS E. BALZLEY.
